QUINONE HAIR DYE COMPOSITIONS

Jerome A. Feit, 5000 N. Kildare Ave., and Aloysius J. Feit, 5001 N. Lowell Ave., Chicago 30, Ill.
No Drawing. Filed Sept. 17, 1957, Ser. No. 684,426
9 Claims. (Cl. 167—88)

This invention relates to the dyeing of hair on the human head and is particularly concerned with new and improved hair dye compositions therefor.

Various types of hair dyes and hair dyeing and coloring compositions have been suggested over a period of many years and various of them have come into use. Among the organic dyes which have found varying favor from time to time in hair dyeing compositions are those of vegetable, coal tar, and synthetic origin, basic and direct dyes, including those of the type of paraphenylenediamine and para-diaminophenol, azo dyes, and triphenylmethane dyes, etc. Formulations based on tannin or pyrogallol with soluble salts of various metals such as lead, silver, iron, nickel, copper, bismuth, mercury, and still others, have at times been used but they have fallen into disfavor due to their poisonous nature, their interference with the cold waving of hair and restrictive Government regulations. The hair dye compositions which are in largest use and which have met with the greatest reception at the present time are those which utilize so-called "para dyes," such as paraphenylenediamine and para-diaminophenol, mentioned above, as well as others of this type such as metaphenylenediamine, and ortho-, meta- and para-toluenediamine, and the acid salts thereof as well, also, as sulfonic derivatives of certain of said "para dyes." The said "para dyes" are conventionally applied to the hair in solution with hydrogen peroxide or the hydrogen peroxide is applied immediately after the subjection of the hair to contact with the "para dyes." Because the "para dyes" are toxic to some persons, it is necessary to resort to the so-called patch test to determine preliminarily whether the particular individual involved may be adversely affected by the hair dye. This, and the requirement by law for the placement of a "caution" notice on the packages of such dyes, has left much to be desired in the way of achieving fully satisfactory hair dye compositions which give good results and are essentially free from toxic effects. Indeed, it may safely be said that no hair dye compositions have yet been evolved which are capable of simple use by the woman in the home which give good dyeing results and which effectively eliminate the problem of toxicity to the user.

Suggestions have also been made broadly to utilize anthraquinone dyes in hair dyeing compositions, but no effective way was found to obtain satisfactory hair dye compositions containing anthraquinone dyes, and such compositions have not gone into commercial use.

In accordance with the present invention, new and highly improved hair dye compositions have been evolved which achieve excellent dyeing results, are simple to use, and are materially freer from toxic effects such as commonly characterize the "para dyes." The hair dye compositions of the present invention are made, for marketing, in the form of dry compositions, and in use are employed particularly in the form of freshly prepared pastes, although they can also, with less convenience, be utilized in the form of freely flowing liquids. They are characterized by the presence, as essential ingredients, of a synthetic nontoxic quinone dye which is or has been rendered water-soluble or water-dispersible, a water-soluble

2

dispersing agent or surface-active agent, a thickening agent, and an alkaline reacting compound.

The synthetic nontoxic quinone dyes which are utilized in accordance with the present invention may contain one, two or three rings, any one or more of which may comprise quinone rings. In order to be effective for the purposes of this invention, the said quinone dyes must be water-soluble or water-dispersible or rendered water-soluble or water-dispersible. Their molecules may contain substituent groups, for instance, hydroxyl, carboxyl, amino, nitro and sulfonic. Such groups serve to enhance the water-solubility of the quinone dyes, the sulfonic groups generally speaking being most effective in this regard but they tend to diminish the affinity of the quinones for the hair. The quinone dyes may also contain alkyl and halogen, such as chlorine and bromine, groups. These substituent groups, as well as various of those previously mentioned, affect not only the water-solubility but also the shades of colors obtained on the hair. Typical or illustrative examples of synthetic nontoxic quinone dyes which produce good results, when used in accordance with the principles of this invention, are benzoquinones, naphthoquinones and anthraquinones such as hydroquinone; 1,4-naphthoquinone; 1,2-naphthoquinone; 2,6-di-25 chloroquinonechlorimide; N-chloro-p-quinone-chlorimide; tert - butylhydroxyquinone; 1,2 - dihydroxyanthraquinone; tetrachloroquinone; 1,2-dihydroxy-3-nitroanthraquinone; 1,4-diaminodihydroanthraquinone; N-chloro-p-quinoneimine; and various mixtures of two or more thereof.

Modifications of the shades of the hair dyes can be obtained by including with the synthetic nontoxic quinones various agents as, for instance, tannic acid and phenols and naphthols such as resorcinol, catechol, 2-amino - 1 - naphthol, 4 - amino - 1 - naphthol and 8-amino-1-naphthol; and aminosalicylic acid. In some cases, the inclusion of certain naphthols has resulted in new dyes or colors as, for example, in the case of 8-amino-1-naphthol and tetrachloroquinone which produces a green shade whereas naphthol alone gives a brown shade and tetrachloroquinone alone gives a tan shade.

The water-soluble dispersing agent or surface active agent serves, among other purposes, to enhance the solubility of the quinones and to increase the affinity of the quinone dyes for the hair. Numerous agents of that type are readily available as, for instance, higher alkyl benzene sulfonates such as dodecyl benzene sodium sulfonate; alkyl naphthalene sulfonates such as nonyl naphthalene sodium sulfonate and isopropyl naphthalene sodium sulfonate; sulfonated esters of alcohols and polybasic acids as, for instance, dioctyl sodium sulfosuccinate, typical of such products being sold under the names "Aerosol OT" and "Decersol OT"; taurates such as sodium N-methyl-N-oleoyl taurate and sodium N-methyl-N-coconut oil fatty acid taurate, such products being sold under the name "Igepon T"; oleic acid ester of sodium isethionate, sold under the name "Igepon AP-75"; fatty alcohol sulfates such as sodium dodecyl sulfate; sulfates of branched chain or secondary alcohols such as 7-ethyl-2-methylundecanol-4 sulfate, sodium salt, and 3,9-diethyl tridecanol-6 sulfate, sodium salt, sold under the name "Tergitol"; naphthalene sulfonic acid condensates sold under the name "Blancol N," and the like.

The thickening agents serve to make a paste of the dye compositions when used for the dyeing of the hair and make for convenient application and prevent the dye composition from running off the hair. No novelty is claimed broadly in using thickening agents in hair dye compositions as this has broadly been known and prac-

ticed in the art. Thickening agents which can be used include, among others, alginates such as sodium alginate of which the product sold under the name "Gelcarin" is a typical example; vegetable gums such as agar and tragacanth; and synthetic thickeners such as sodium carboxymethylcellulose. It has been found that it is especially desirable to include bentonite in the hair dye compositions of the present invention, the bentonite serving to give desired body to the hair dye composition.

The alkaline reacting compound, when used in combination with the other ingredients of the hair dye compositions of this invention, serves to increase the affinity of the hair for the dye ingredients. It is particularly preferred to use an alkaline reacting compound with oxidizing properties. Suitable alkaline reacting compounds are trisodium phosphate, sodium carbonate, tetrasodium pyrophosphate, sodium hexametaphosphate, sodium tripolyphosphates and sodium perborate. Sodium perborate is especially satisfactory because of its mildness, stability and the relatively low pH of its solutions, namely pH 9.9. It is particularly desirable that the alkalinity of the dye compositions fall within the range of 8 to 10.5.

The proportions of the ingredients are variable within reasonable limits. In general, the proportions set forth below, while not intended as limiting the invention, produce dye compositions which give excellent results. The percentages stated are by weight:

	Percent
Synthetic nontoxic quinone dye (or dye mixture)	2 to 25
Water-soluble surface active agent	15 to 40
Thickening agent	3 to 15
Alkaline reacting compound	2 to 8

The especially preferred hair dye compositions of the present invention fall within the following compositional limits:

	Percent
Synthetic nontoxic quinone dye (or dye mixture)	8 to 25
Water-soluble surface active agent	25 to 35
Sodium alginate	8 to 12
Bentonite	20 to 40
Sodium perborate	4 to 6

By increasing the amount of sodium alginate or the like and correspondingly reducing the bentonite, varying adjustments can be made in the thickness of the paste. It will be understood that various supplemental ingredients can be added, including perfumes, for obtaining special effects without departing from the novel teachings and principles set forth herein.

The following examples are illustrative of hair dye compositions made in accordance with this invention. It will be understood that various other hair dye compositions can readily be evolved following the guiding principles and teachings set forth herein. All parts listed are by weight.

EXAMPLE 1

Light Auburn

Tert-butylhydroquinone	10.0
2-hydroxy-1,4-naphthoquinone	10.0
Dodecyl benzene sodium sulfonate	35.0
Sodium alginate	10.0
Sodium perborate	5.0
Bentonite	30.0

EXAMPLE 2

Dark Auburn

1,2-dihydroxyanthraquinone	10.0
1,4-diaminodihydroanthraquinone	15.0
Isopropyl naphthalene sodium sulfonate	35.0
Sodium alginate	10.0
Sodium perborate	5.0
Bentonite	25.0

EXAMPLE 3

Dark Ash Blonde

1,2-naphthoquinone	7.0
Resorcinol	7.0
Nonyl naphthalene sodium sulfonate	35.0
Sodium alginate	10.0
Sodium perborate	5.0
Bentonite	36.0

EXAMPLE 4

Reddish Blonde

Hydroquinone	10.0
Dodecyl benzene sodium sulfonate	35.0
Sodium alginate	10.0
Sodium perborate	5.0
Bentonite	40.0

EXAMPLE 5

Neutral Brown

2,6-dichloroquinonechlorimide	13.0
Tert-butylhydroquinone	8.0
Sodium N-methyl-N-oleoyl taurate	35.0
Sodium alginate	10.0
Sodium perborate	5.0
Bentonite	29.0

EXAMPLE 6

Reddish Brown

1,2-naphthoquinone	10.0
p-toluquinone	10.0
Dodecyl benzene sodium sulfonate	35.0
Sodium alginate	10.0
Sodium perborate	5.0
Bentonite	30.0

EXAMPLE 7

Golden Blonde

Hydroquinone	8.0
2-amino-1,4-naphthoquinone	0.5
Isopropyl naphthalene sodium sulfonate	35.0
Sodium alginate	10.0
Sodium perborate	5.0
Bentonite	41.5

EXAMPLE 8

Steel Grey

2-amino-1-naphthol	1.0
Tetrachloroquinone	2.0
1,4-diaminoanthraquinone	3.0
Naphthalene sulfonic acid condensate	35.0
Sodium alginate	10.0
Sodium perborate	5.0
Bentonite	44.0

EXAMPLE 9

Pale Blonde

Hydroquinone	2.5
Aminosalicylic acid	2.5
Sodium N-Methyl-N-oleoyl taurate	35.0
Sodium alginate	10.0
Sodium perborate	5.0
Bentonite	45.0

EXAMPLE 10

Bright Red

1,2-dihydroxyanthraquinone	10.0
1,4-diaminodihydroanthraquinone	1.0
Oleic acid ester of sodium isethionate	35.0
Sodium alginate	10.0
Sodium perborate	5.0
Bentonite	39.0

5

EXAMPLE 11

Golden Brown

1,2-naphthoquinone	5.0
Resorcinol	5.0
Diethyl sodium sulfosuccinate	35.0
Sodium alginate	10.0
Sodium perborate	5.0
Bentonite	40.0

EXAMPLE 12

Black

N-chloro-p-quinoneimine	40.0
4-amino-1-naphthol	1.0
8-amino-1-naphthol	0.4
Tetrachloroquinone	0.6
Lauryl sodium sulfate	35.0
Sodium alginate	10.0
Sodium perborate	5.0
Bentonite	8.0

EXAMPLE 13

Light Ash Brown

1,2-naphthoquinone	10.0
Resorcinol	20.0
Dodecyl benzene sodium sulfonate	35.0
Sodium alginate	10.0
Sodium perborate	5.0
Bentonite	20.0

EXAMPLE 14

Dark Brown

N-chloro-p-quinoneimine	15.0
8-amino-1-naphthol	5.0
Tetrachloroquinone	10.0
Dodecyl benzene sodium sulfonate	35.0
Sodium alginate	10.0
Sodium perborate	5.0
Bentonite	20.0

In dyeing the hair with the novel hair dye compositions of the present invention, 1 gram of the hair dye composition of any of the foregoing examples is admixed with 4.5 cc. of water at 40 to 50 degrees C. The resulting paste is then applied to the hair and allowed to remain in contact therewith for from about 15 to 30 minutes while maintaining the temperature of the scalp at above 40 degrees C. to develop the full shade. Longer contact times are used where lower application temperatures are employed. The dye paste can be applied to the hair by means of a comb, brush, swab or the like. After the dye paste has been in contact with the hair for about 15 to 30 minutes, in the usual case, the hair is rinsed with lukewarm water to remove excess dye composition and is then shampooed.

What is claimed as new and desired to be protected by Letters Patent of the United States is:

1. A hair dye in the form selected from the group consisting of an aqueous paste and of a dry composition which is adapted upon admixture with water to form a paste for application to the hair, said composition comprising a mixture containing a synthetic nontoxic water-soluble to dispersible quinone dye, a water-soluble surface active agent, bentonite, sodium alginate, and an alkaline reacting compound.

2. A hair dye in the form selected from the group consisting of an aqueous paste and of a dry composition which is adapted upon admixture with water to form a paste for application to the hair, said composition comprising a mixture containing a synthetic nontoxic water-soluble to dispersible quinone dye, a water-soluble dispersing surface active agent, bentonite, sodium alginate, and an alkaline reacting oxidizing agent.

3. A hair dye in the form selected from the group consisting of an aqueous paste and of a dry composition

which is adapted upon admixture with water to form a paste for application to the hair, said composition comprising a mixture containing a synthetic nontoxic water-soluble to dispersible quinone dye, a water-soluble dispersing surface active agent, bentonite, sodium alginate, and sodium perborate.

4. A hair dye in the form selected from the group consisting of an aqueous paste and of a dry composition which is adapted upon admixture with water to form a paste for application to the hair, said composition, on the dry basis, containing the following ingredients in substantially the following percentages by weight:

	Percent
Synthetic nontoxic water-soluble to dispersible	
quinone dye	2 to 25
Water-soluble surface active agent	15 to 40
Thickening agent	3 to 15
Alkaline reacting compound	2 to 8

5. A hair dye composition in accordance with claim 4, wherein the quinone dye is selected from the group consisting of 1,4-naphthoquinone; 1,2-naphthoquinone; 2,6-dichloroquinonechlorimide; N-chloro-p-quinone - chlorimide; tert-butylhydroxyquinone; 1,2-dihydroxyanthraquinone; tetrachloroquinone; 1,2-dihydroxy-3-nitroanthraquinone; 1,4-diaminodihydroanthraquinone; N-chloro-p-quinoneimine; and compatible mixtures thereof.

6. A hair dye in the form selected from the group consisting of an aqueous paste and of a dry composition which is adapted upon admixture with water to form a paste for application to the hair, said composition, on the dry basis, containing the following ingredients in substantially the following percentages by weight:

	Percent
Synthetic nontoxic water-soluble to dispersible	
quinone dye	8 to 25
Water-soluble surface active agent	15 to 40
Sodium alginate	3 to 15
Alkaline reacting oxidizing agent	2 to 8

7. A hair dye in the form selected from the group consisting of an aqueous paste and of a dry composition which is adapted upon admixture with water to form a paste for application to the hair, said composition, on the dry basis, containing the following ingredients in substantially the following percentages by weight:

	Percent
Synthetic nontoxic water-soluble to dispersible	
quinone dye	8 to 25
Water-soluble surface active agent	15 to 40
Sodium alginate	3 to 15
Sodium perborate	2 to 8

8. A hair dye in the form selected from the group consisting of an aqueous paste and of a dry composition which is adapted upon admixture with water to form a paste for application to the hair, said composition, on the dry basis, containing the following ingredients in substantially the following percentages by weight:

	Percent
Synthetic nontoxic water-soluble to dispersible	
quinone dye	8 to 25
Water-soluble surface active agent	25 to 35
Sodium alginate	8 to 12
Bentonite	20 to 40
Sodium perborate	4 to 6

9. A hair dye composition in accordance with claim 8, wherein the quinone dye is selected from the group consisting of 1,4-naphthoquinone; 1,2-naphthoquinone; 2,6-dichloroquinonechlorimide; N-chloro-p-quinone - chlorimide; tert-butylhydroxyquinone; 1,2-dihydroxyanthraquinone; tetrachloroquinone; 1,2-dihydroxy-3-nitroanthraquinone; 1,4-diaminodihydroanthraquinone; N-chloro-p-quinoneimine; and compatible mixtures thereof.
